JOHN P. LEASK, OF GLENBROOK, CONNECTICUT, ASSIGNOR TO PEABODY ENGINEERING CORPORATION, OF NEW YORK, N. Y., A CORPORATION OF NEW YORK

OIL BURNING SYSTEM

Application filed July 21, 1928. Serial No. 294,464.

My invention relates to oil burning systems and more particularly to means for varying the capacity of the atomizer, that is, for varying the amount of oil atomized per burner per hour. The desired variation is effected by providing the atomizer with a plurality of independent oil passages and controlling the ports of said passages by a valve or valves, the position of which is determined by the pressure of the oil in the supply line. The invention will be understood by reference to the accompanying drawings in which Fig. 1 is a longitudinal section on the plane of the line 1—1 of Fig. 2 through the rear end of an atomizer having means therein for controlling the distribution of the oil to the tip; Fig. 2 is a transverse section on the plane of the line 2—2 of Fig. 1; Fig. 3 is a transverse section on the plane of the line 3—3 of Fig. 1; Fig. 4 is a view similar to Fig. 1 on the plane of the line 4—4 of Fig. 5, showing a modified form of atomizer; Fig. 5 is a transverse section on the plane of the line 5—5 of Fig. 25; Fig. 6 is a diagrammatic view of a boiler front showing the layout of a system in which the atomizers may be used. Similar reference numerals indicate similar parts in the several views.

In Fig. 6 I have, for convenience of description, illustrated the layout of a system in which the invention may be employed. In this figure the letter *a* designates a boiler having three atomizers *b*, *c*, and *d* installed therein. The source of fuel supply is through main line *e* to branches *e'*, *e''*, *e'''*. The main line may have therein a valve *f* automatically controlled by the steam pressure through a diaphragm regulator *g*. Manually operated valves *h* may be placed in the main line and in a by-pass *i* thus permitting the oil to flow to the branch connections either through the main line or through the by-pass. It is to be understood, of course, that the installation may be equipped with any number of atomizers and that the means hereinafter described may be set to deliver the oil from the main supply line at the same pressure to all of the atomizers of the installation. Stated generally, my invention utilizes the pressure of the incoming oil itself to control the amount permitted to flow to the atomizer. This control may be effected at any desired point in the oil supply line. One means for so doing is illustrated in Figs. 1, 2, and 3, in which the numeral 1 designates a portion of a burner barrel which, in practice, will be connected to the main supply line directly when there is but one atomizer, or through a branch pipe when there are a number of atomizers in the installation. The burner barrel is exteriorly threaded at its rear end to receive a cap 2 and is bevelled as shown at 3 to provide a seat for a plug 4. The face of the plug is preferably flat and upon it is seated a tip 5. The latter has a bevelled shoulder at 5' so that the tip will be centered and held in proper position when the cap is screwed upon the burner barrel. A dowel pin 6 secured to the plug 4 and entering a hole in the tip insures proper registration of passages in the plug and tip as hereinafter described.

The tip is formed with a central chamber 7 and a discharge orifice 8. Formed in the flat face of the tip, and entering substantially tangentially to the wall of chamber 7, are ducts 9, 10, 11 and 12. When the parts are assembled, these ducts are in communication, respectively, with passages 13, 14, 15 and 16 in the extension 17 of the plug 4. The said passages are closed at their forward ends and open at their rear ends as shown in Fig. 1. The extension 17 is formed with a chamber 18 in the end of which is a fixed bushing 19 to limit the outward movement of a valve 20 slidably fitted within said chamber. Between said valve and the rear end wall of chamber 18 is a spring 21 adapted to normally hold the valve against bushing 19.

The passages 13, 14, 15 and 16 communicate with chamber 18 through ducts 13', 14', 15', and 16', respectively, in the wall between said chamber and passages. These ducts are located along the wall of chamber 18 a suitable distance apart and in different planes as viewed in Fig. 1. By reason of the concentric disposition of the passages 13, 14, 15 and 16 around the chamber 18 the admission of

oil from the burner barrel to chamber 18, and the outflow of the oil from said chamber, is determined by the position of valve 20 under the pressure of the entering oil. The tension of spring 21 is so adjusted that when the oil supply in the main line is completely cut off, valve 20 will be seated against bushing 19. When the oil supply line is open, the position of valve 20 in chamber 18 will be determined by the pressure of the oil and the valve will be moved, against spring 21, to uncover one or more of the ports of the ducts 13', 14', 15', and 16'.

Assuming a line pressure of 50 lbs. per square inch, the duct 13' will be so located that the movement of valve 20, under such pressure will open the port of said duct to permit the flow of oil from chamber 18 to passage 13 only. When that occurs the oil will enter tip chamber 7 through tangential duct 9 and will escape through the discharge orifice 8. Under a pressure of say 100 lbs. per square inch, the valve 20 will be moved to open duct 14' thus admitting an additional amount of oil which will reach chamber 7 through tangential duct 10. Upon a further increase in the oil pressure, the ducts 15' and 16' will be opened to thus admit the maximum amount of oil to the tip chamber. With the valve 20 at the extreme outward limit of its movement a decrease in the capacity of the atomizer will be effected by reducing the oil pressure and thus closing one or more of the ducts leading from the chamber 18 to the passages 13, 14, 15, and 16. As the oil pressure is decreased the spring 21 will act to move the valve toward its seat on bushing 19.

From the foregoing description it will be seen that I secure a wide range in capacity by successively opening or closing a series of passages leading to the tip chamber and determine such opening and closing by the pressure of the oil in the main supply line.

Where there are a plurality of atomizers the tension of the several springs 21 may be the same or different. If the same, the valves 20 will, of course, be moved to the same extent in all of the atomizers at the same time as the main line pressure is varied. If desired, however, the tension of the springs in the several atomizers may differ one from the other so as to vary the extent of movement of its corresponding valve 20. In that case the capacities of the several atomizers will be correspondingly varied.

While I have shown four passages surrounding chamber 18 it is obvious that there may be a greater or less number with corresponding changes in the number of tangential ducts leading into the tip chamber 7.

Instead of forming the plug extension with a central supply chamber 18, I may employ the construction illustrated in Figs. 4 and 5

in which the plug extension 17' is formed with four independent passages 22, 23, 24 and 25 opening directly from the burner barrel 1. Fixed in the outer end of each of said passages is a bushing 26 having ribs 26' projecting therefrom to form a raceway for ball valve 27. This valve is normally held on its seat on the bushing 26 by a spring 27 bearing at its other end against the end wall of the passage.

The burner barrel, cap, tip, and tangential passages are the same as in Fig. 1. The passages 22, 23, 24 and 25 communicate with the respective tangential passages to deliver the oil to the tip chamber 7. In this modified form, the amount of oil admitted to the tip chamber is regulated by the tension of the springs 28 in the several passages. That is, assuming the spring 28 in passage 22 of such tension as to permit the opening of valve 27 under a pressure of 50 lbs. per square inch, a certain number of pounds of oil will be permitted to flow to the tip chamber. The spring 28 in the passage 23 will be adjusted so as to permit the opening of the corresponding valve 27 under a pressure of say 100 lbs. per square inch, thus admitting an additional amount of oil to the tip chamber. Similarly the springs in the passages 24 and 25 may be adjusted to permit the opening of the corresponding valves when the oil pressure reaches 150 and 200 lbs. per square inch, respectively.

As far as the principle is concerned, the method of operation of the two forms of atomizers shown is the same. In both it may be said that the oil is delivered to the atomizer from the main supply line through independent passages, and that the admission of oil to said passages is automatically controlled by the pressure of the oil in the main line.

What I claim is:

1. An oil burning system comprising a source of fuel supply, an atomizer having a tip and a plurality of independent oil passages leading thereto, a pipe line connection from the source of supply to the atomizer, and means for successively opening said passages actuated by the pressure of the oil in the pipe line.

2. An oil burning system comprising a source of fuel supply, an atomizer having a tip and a plurality of independent oil passages leading thereto, a pipe line connection from the source of supply to the atomizer, a valve in said line, and means to permit the movement of said valve upon variations in the oil pressure to open or close said passages successively.

3. An oil burning system comprising a source of fuel supply, an atomizer having a tip and a plurality of independent oil inlet passages leading thereto, an oil chamber the wall of which has ducts to admit the oil from

- said chamber to said passage, and means controlled by variations in the pressure of the oil in the pipe line to effect the opening or closing of said ducts successively.
5. An oil burning system comprising a source of fuel supply, an atomizer having a tip and a plurality of independent passages leading to the tip, a pipe connection between the source of supply and the atomizer, independent connections between said pipe and said passages, and a valve controlled by variations in the pressure of the oil in the pipe connection to successively open the ports of said independent connections.
10. An oil burning system comprising a source of fuel supply, an atomizer having a tip with a chamber therein and a plurality of ducts leading to said chamber, a plug having a plurality of passages corresponding to said ducts, said plug having an oil chamber and openings in the wall thereof to said passages, and a valve in said chamber controlled by variations in the pressure of the oil to successively open the ports of said openings.
15. An oil burning system comprising a source of fuel supply, an atomizer having a tip and a plurality of independent oil passages leading thereto, an oil chamber the wall of which is formed with openings spaced in the direction of flow to admit oil to said passages, and a valve in said chamber movable by variations in the pressure of the incoming oil to successively open or close said openings.
20. An oil burning system comprising a source of fuel supply, an atomizer having a tip and a plurality of independent oil inlet passages leading thereto, a burner barrel, an oil chamber within said barrel the wall of which has a plurality of ports in spaced relation leading from said chamber to said passages, and a valve in said chamber controlled by variations in the pressure of the incoming oil to open and close said ports successively.
25. An atomizer having a tip and a plurality of independent oil inlet passages leading thereto, a pipe line connection from a source of supply to the atomizer, a spring pressed valve in said line adapted to normally close all of said passages and movable to open said passages successively by variations in the pressure of the incoming oil.
30. Signed at the city of New York, in the county of New York and State of New York this 19th day of July, A. D. 1928.
